RAILWAY SIGNALING SYSTEM

Howard A. Thompson, Edgewood, Pa., assignor to
 The Union Switch & Signal Company, Swiss-
 vale, Pa., a corporation of Pennsylvania

Application January 8, 1943, Serial No. 471,681

10 Claims. (Cl. 346—63)

My invention relates to a railway signaling system of the type in which coded alternating current energy is supplied to the rails of a track section to control cab signal apparatus on a locomotive in the track section.

In systems of this type coded energy of a distinctive code frequency, as for example, energy of 75 code frequency, is supplied to the rails of the track section in the rear of an occupied section to cause the cab signal apparatus on a locomotive in that section to display a restrictive proceed indication, as for example an approach indication. However, with previous systems of this type the engineer has no means of knowing when he is approaching the end of the section in the rear of an occupied section unless wayside signals or markers are provided to mark the limits of the track sections, since the locomotive cab signal apparatus will provide the approach indication until the locomotive enters the occupied section.

An object of this invention is to provide a system of the type described which is arranged so that the cab signal apparatus on a locomotive in the adjacent section in the rear of an occupied section will display its approach indication until the locomotive advances to within a predetermined distance of the exit end of the section, and so that the locomotive cab signal apparatus will thereafter display its most restrictive indication.

Another object of the invention is to provide a system of the type described and incorporating means to supply to the section rails during the "off" periods in the code, alternating current energy of substantially lower voltage than that supplied to the section rails during the "on" periods in the code to thereby prevent operation of code responsive apparatus on a locomotive in the section only after the locomotive has advanced a substantial part of the distance towards the exit end of the track section.

A further object of the invention is to provide a system of the type described and incorporating means to check the supply of energy to the section rails during the "off" periods in the code and to prevent the supply of energy to the section rails during the "on" periods in the code unless energy is also supplied to the section rails during the "off" periods in the code.

Other objects of the invention and features of novelty will be apparent from the following description taken in connection with the accompanying drawing.

I shall describe two forms of railway signaling apparatus embodying my invention, and shall

then point out the novel features thereof in claims.

In the drawing,

Fig. 1 is a diagram of a section of railway track equipped with apparatus embodying my invention, and

Fig. 2 is a diagram of a modification which I may employ.

Similar reference characters refer to similar parts in both views.

In practicing my invention I provide a principal track transformer from which there is supplied to the rails of a track section during the picked-up periods of the contacts of a coding device energy of a voltage effective to operate the cab signal apparatus on a locomotive at any point in the track section. In addition, I provide an auxiliary track transformer from which there is supplied to the rails of a section during the released periods of the coding device contacts, when the adjacent section in advance is occupied, energy of a lower voltage which is effective to operate the cab signal apparatus on a locomotive only after the locomotive has advanced to within a predetermined distance of the exit end of the section, while I provide a relay governed by supply of energy from the auxiliary track transformer to the section rails and controlling the supply of energy to the principal track transformer.

Referring to Fig. 1 of the drawing, there is shown therein a stretch of railway track having track rails 1 and 2 over which traffic normally moves in the direction indicated by the arrow, that is, from left to right. The rails of the track stretch are divided by insulated joints 3 into track sections for signaling purposes. One such section, which is designated 5T, and portions of the adjoining sections 4T and 6T, are shown in the drawing.

As shown, the track stretch is without wayside signals and movement of trains through the track stretch is governed by cab signal apparatus on the locomotives which are operated in the track stretch. Although this invention is intended primarily for use in track stretches having cab signals only, it is not limited to use in such situations, and is equally applicable to track stretches equipped with wayside as well as cab signals.

The construction and operation of the cab signal apparatus on the locomotives is not a part of this invention and any appropriate form of apparatus may be employed for this purpose. One form of cab signal apparatus which may be

employed is shown in Letters Patent of the United States No. 1,986,679, granted January 1, 1935, to Lloyd V. Lewis. The apparatus shown in that patent includes receiver coils mounted on the locomotive over the track rails in advance of the leading wheels of the locomotive. Alternating energy supplied to the track rails at the exit end of the section flows between the track rails through the wheels and axles of the locomotive, while this energy flowing in the portions of the track rails beneath the receiver coils causes energy to be induced in the receiver coils. The energy induced in the receiver coils is amplified and is employed to operate signal apparatus on the locomotive. The locomotive equipment is arranged so that it will operate to provide a proceed signal indication only when coded or periodically interrupted energy is supplied thereto, and so that it will provide its most restrictive indication when no energy or steady energy is supplied thereto.

In addition, in order to prevent response of the locomotive cab signal apparatus to foreign current, the equipment on the locomotives is arranged so that it will respond to energy in the track rails only when the energy in the portion of the track rails beneath the receiver coils exceeds a predetermined minimum. This value is determined by the amount of current flowing between the track rails through the wheels and axles of the locomotive, and is termed the "axle" current.

The track section 5T is provided with a track circuit comprising a code following track relay 5TR to which is supplied coded circuit current from a track battery 5TB. Means is provided for supplying coded energy to the section rails from a principal track transformer 5TT, and to also supply energy to the section rails from the auxiliary track transformer 5TTA over a circuit which includes an auxiliary relay 5AR in series therewith.

The principal track transformer 5TT is proportioned so that the voltage of the energy supplied from the secondary winding thereof to the section rails is such as to cause the axle current at the entrance end of the section to be high enough to insure operation of the cab signal apparatus on a locomotive at the entrance end of the section under the most adverse ballast conditions.

The auxiliary track transformer 5TTA is proportioned so that the voltage of the energy supplied from the secondary winding thereof to the track rails is such as to cause too little axle current to flow in the portion of the section rails adjacent the entrance end of the section to affect the cab signal apparatus on a locomotive. As a locomotive advances in the track section, the value of the axle current produced by energy supplied from both transformers increases, and when the locomotive reaches a point some distance, such as 2500 feet, from the exit end of the section, the axle current resulting from energy supplied from transformer 5TTA will increase to a value effective to operate the locomotive cab signal apparatus.

The supply of energy to the track section is governed by a coding relay 5CTM, while the supply of energy to relay 5CTM is governed by a relay 6H which is governed by traffic conditions in section 6T so as to be picked up or released according as section 6T is vacant or is occupied.

The relay 6H has associated therewith continuously operating coding devices 180CT and

75CT which have contacts which are actuated between their picked-up and released positions at rates such as to provide coded energy consisting of 180 or 75 energy impulses which are separated by periods of substantially equal duration in which no energy is supplied.

The alternating current supplied to the track transformers may be supplied from any suitable source, not shown, the terminals of which are designated BX and CX in the drawing.

The equipment at each end of the track section includes a source of direct current, not shown, the terminals of which are designated B and C.

The equipment is shown in the condition which it assumes when the track stretch is vacant. At this time the relay 6H is picked up and its contact 10 establishes the circuit controlled by code transmitter 180CT for supplying energy to relay 5CTM and the contacts of relay 5CTM operate to supply energy of 180 code frequency to the rails of section 5T. In addition, at this time contact 11 of relay 6H establishes a circuit to supply energy to the primary winding of the principal track transformer 5TT, and interrupts the circuit of the auxiliary track transformer 5TTA. During the picked-up periods of the contact 12 of coding relay 5CTM energy is supplied to the rails of section 5T from the track battery 5TB and from the principal track transformer 5TT. During the released periods of contact 12 of relay 5CTM the circuit of the secondary winding of auxiliary track transformer 5TTA is established, but as the circuit of the primary winding of transformer 5TTA is interrupted by contact 11 of relay 6H energy is not supplied from transformer 5TTA to the section rails.

The energy supplied from track battery 5TB to the section rails feeds to track relay 5TR and operates it so that energy is supplied through the decoding transformer 5DT to relay 5H in the manner explained in Letters Patent of the United States No. 2,237,788 to Frank H. Nicholson and Leslie R. Allison. Accordingly, the contacts of relay 5H are picked up and may control the supply of energy to the rails of section 4T in the same manner that relay 6H controls the supply of energy to section 5T.

When a train moving in the normal direction of traffic enters section 5T, the track relay 5TR ceases to follow code and relay 5H releases. In addition, when the train enters section 5T, the coded alternating current of 180 code frequency supplied from the principal track transformer 5TT to the rails of section 5T operates the cab signal apparatus on the locomotive of the train so that a clear signal is displayed in the locomotive cab.

As pointed out above, energy is not supplied from the auxiliary track transformer 5TTA to the section rails at this time. Accordingly, the cab signal apparatus on the locomotive of the train in section 5T will operate in the customary manner to provide the clear signal indication as the locomotive proceeds through the track section.

When the train enters section 6T, the relay 6H releases and its contact 10 transfers control of coding relay 5CTM from the contact of code transmitter 180CT to the contact of code transmitter 75CT. In addition, contact 11 of relay 6H interrupts the circuit established by its front contact for supplying energy to the principal track transformer 5TT and establishes a circuit for supplying energy to the auxiliary track transformer 5TTA, and to the principal track trans-

former provided the contact of relay 5AR is picked up.

As energy is supplied to the primary winding of the auxiliary track transformer 5TTA, energy is supplied to the section rails from the secondary winding of this transformer over the circuit which is traced from one terminal of the transformer secondary winding to rail 1, and from the other terminal of the transformer secondary winding through one leg of the rectifier 5R, winding of auxiliary relay 5AR, another leg of the rectifier 5R, and back contact 12 of relay 5CTM to rail 2.

As a result of the supply of energy from transformer 5TTA to the section rails over the circuit which includes the winding of relay 5AR in series therewith, contact 14 of relay 5AR is picked up and establishes a circuit to supply energy to the primary winding of transformer 5TT. The relay 5AR is of a type the contacts of which are slow in releasing so that its contact 14 remains picked up and maintains the circuit of transformer 5TT during the picked-up periods of the contact 12 of coding relay 5CTM.

Accordingly, when section 6T is occupied and relay 6H is released, coding relay 5CTM is operated at the 75 code speed, while energy is supplied from transformer 5TTA to the section rails during the released periods of contact 12 of relay 5CTM, and energy is supplied to the section rails from track battery 5TB and the transformer 5TT during the picked-up periods of contact 12.

When the train under consideration vacates section 5T, the energy supplied from track battery 5TB to the section rails feeds to track relay 5TR and operates it so that energy is supplied through the decoding transformer 5DT to relay 5H. When the train advances far enough to vacate section 6T, relay 6H is picked up and transfers control of relay 5CTM from code transmitter 75CT to code transmitter 180CT, while contact 11 of relay 6H interrupts the circuits for supplying energy to transformers 5TTA and 5TT and establishes the circuit for supplying energy to the transformer 5TT.

If while a train is in section 6T a second train enters section 5T the cab signal equipment on the locomotive of the second train will respond to the energy of 75 code frequency supplied from the principal track transformer 5TT to the section rails and will provide the approach indication as long as the train is in the portion of section 5T adjacent the entrance end of the section.

At this time energy is also supplied to the section rails from the auxiliary track transformer 5TTA, but as explained above, the voltage of the energy supplied from the auxiliary track transformer is so low that energy supplied from this transformer has no effect on the cab signal equipment on a locomotive in the portion of section adjacent the entrance end of the section.

When the train advances to within a predetermined distance of the exit end of section 5T, the energy supplied from the auxiliary track transformer 5TTA to the section rails, and flowing in the portion of the track rails beneath the receiver coils on the locomotive, increases to a value high enough to operate the locomotive cab signal equipment. When this occurs, it has the effect of causing steady energy to be supplied to the locomotive cab signal apparatus since energy is supplied from transformer 5TT during the picked-up periods of contact 12 of relay 5CTM and is supplied from transformer 5TTA during the released periods of contact 12 of relay 5CTM.

The locomotive cab signal equipment must be supplied with coded energy in order to provide a proceed indication, and when steady energy is supplied thereto the locomotive equipment operates to provide its stop or most restrictive indication.

Accordingly, when a train enters the section in the rear of an occupied section, the cab signal equipment on the locomotive of the train operates to provide its approach indication until the train advances to within a predetermined distance of the exit end of the section, after which the cab signal equipment provides its stop or most restrictive indication. This will inform the engineer on the locomotive of the fact that he is approaching the end of the track section and is about to enter an occupied section. The operation of the system, therefore, is such that the cab signal apparatus on a locomotive operates to provide the most restrictive indication while the train is still in an unoccupied section, and at a point some distance from the entrance to an occupied section, so that the engineer has ample opportunity to stop or reduce the train speed to a safe speed before he reaches the occupied section.

The point to which a train must advance in the section before the current supplied from transformer 5TTA increases to a value effective to operate the locomotive cab signal apparatus will vary with changing ballast conditions. The various parts of the apparatus may be selected and adjusted so that under the most adverse ballast conditions the energy supplied from transformer 5TTA will operate the cab signal apparatus on a locomotive for at least the selected distance, such as 2500 feet from the exit end of the section, so that a train will always have at least this much warning that it is approaching the end of the section.

Under favorable ballast conditions the energy supplied from the auxiliary track transformer 5TTA will be effective to operate the cab signal apparatus on a locomotive somewhat farther than the minimum distance of 2500 feet from the entrance end of the track section. Accordingly, under favorable ballast conditions a train will receive the restrictive indication somewhat sooner than it is received under adverse ballast conditions, but as a train will always receive the minimum warning that it is approaching an occupied section, the system is entirely safe and variations in the point at which the restrictive indication is given are not objectionable.

If there should be a failure in the supply of energy from the auxiliary track transformer 5TTA, and energy should continue to be supplied from the principal track transformer 5TT, the cab signal apparatus on a locomotive would continue to provide the approach indication throughout the entire length of section 5T, and the equipment would fail to operate in the normal manner to warn the engineer when his train approaches an occupied section. This system includes means to prevent such a failure.

In the system shown in Fig. 1, energy is supplied from the auxiliary track transformer 5TTA to the section rails over a circuit which includes the winding of relay 5AR in series therewith, so that contact 14 of relay 5AR is picked up when and only when energy is supplied from transformer 5TTA to the section rails. Contact 14 of relay 5AR controls the supply of energy to transformer 5TT, so that when relay 6H is re-

leased, energy will not be supplied to transformer 5TT, and, therefore, will not be supplied from transformer 5TT to the section rails, unless energy is being supplied from transformer 5TTA to the section rails. This insures that when a train enters section 5T at a time when section 6T is occupied, energy will not be supplied from transformer 5TT to the section rails to cause the display of the approach indication by the locomotive cab signal equipment when the train is in the portion of the track section adjacent the entrance end of the section unless energy is also supplied to the section rails from transformer 5TTA to cause the locomotive cab signal equipment to provide its most restrictive indication when the train advances into the portion of the track section adjacent the exit end of the section.

Accordingly, if for any reason energy is not supplied from transformer 5TTA to the section rails when section 6T is occupied, the cab signal apparatus on a locomotive will display its most restrictive indication as soon as the locomotive enters section 5T and the engineer will have ample warning that he is approaching an occupied section.

The system provided by this invention is also adapted for use in track stretches in which coded alternating current energy is employed in the track circuits to operate the track relays as well as for the control of cab signals, and Fig. 2 is a diagram illustrating such a modification.

The system shown in Fig. 2 is similar to that shown in Fig. 1 but differs therefrom in that the track relay 5TR is connected to the track rails through a transformer and a rectifier, while the transformers 5TT and 5TTA are connected to the track rails through a transformer 5ST, instead of being directly connected to the section rails.

The equipment is shown in the condition which it assumes when the track stretch is vacant. At this time relay 6H is picked up and its contact 10 establishes the circuit controlled by a contact of code transmitter 135CT for supplying energy from the principal transformer 5TT to transformer 5ST and thus to the section rails.

The energy supplied from transformer 5TT to the section rails feeds to the track relay 5TR and operates it so that energy is supplied through the decoding transformer 5DT to relay 5H to keep the contacts of relay 5H picked up.

When a train moving in the normal direction of traffic enters section 5T, the track relay 5TR is shunted and relay 5H releases, while the cab signal apparatus on the locomotive of the train responds to the coded alternating current energy supplied to the section rails and provides the clear indication.

When the train advances into section 6T, relay 6H releases and contact 10 interrupts the circuit controlled by the contact of code transmitter 135CT for supplying energy to the rails of section 5T, and establishes the circuit controlled by a contact of code transmitter 15CT. During the released periods of the contact of code transmitter 15CT energy is supplied from transformer 5TTA to transformer 5ST over the circuit including the rectifier 5R and the winding of relay 5AR in series therewith. Accordingly, contact 14 of relay 5AR is picked up so that during the picked-up periods of the contact of code transmitter 15CT energy is supplied from transformer 5TT to transformer 5ST over the circuit which includes front contact 14 of relay 5AR.

The energy supplied from transformer 5TTA

to the section rails is of substantially lower voltage than that supplied from transformer 5TT, and is of such value that too little energy is supplied therefrom to the track relay 5TR to maintain the contacts of the track relay picked up. Accordingly, when section 5T is vacated, the contacts of relay 5TR pick up during the picked-up periods of code transmitter 15CT, at which time energy is supplied from transformer 5TT, while the contacts of relay 5TR release during the released periods of code transmitter 15CT, at which time energy is supplied from transformer 5TTA. As a result of code following operation of relay 5TR energy is supplied through the decoding transformer 5DT and the contacts of relay 5H are picked up.

When the train vacates section 6T, relay 6H picks up and its contact 10 transfers control of the supply of energy to section 6T from code transmitter 15CT to code transmitter 135CT and energy of 135 code frequency is supplied from transformer 5TT to the section rails, while the supply of energy from transformer 5TTA to the section rails is cut off and relay 5AR releases.

If while section 6T is occupied a second train enters section 5T, the cab signal equipment on the locomotive of the second train will respond to the energy of 135 code frequency supplied from transformer 5TT to the section rails and will provide the approach indication as long as the train is in the portion of section 5T adjacent the entrance end of the section. As long as the train is in the portion of the track section 5T adjacent the entrance end of the section, the energy supplied from transformer 5TTA to the section rails and flowing in the track rails beneath the receiver coils on the locomotive is too small in value to affect the locomotive cab signal apparatus. When the train advances a predetermined distance in the track section, the energy from transformer 5TTA flowing in the track rails beneath the receiver coils on the locomotive will increase to a value high enough to operate the cab signal apparatus and the indication provided by the cab signal equipment will be changed from the approach to the stop or most restrictive indication.

If, for any reason, energy is not supplied from transformer 5TTA to the section rails when section 6T is occupied, relay 5AR will be released and will prevent the supply of energy from transformer 5TT to the section rails. This prevents the display of the approach indication by the cab signal apparatus on a locomotive in the portion of section 5T adjacent the entrance end of the section unless the wayside equipment is functioning in the proper manner to cause the locomotive cab signal apparatus to display its most restrictive indication when the locomotive advances into the portion of the track section adjacent the exit end of the section.

Although I have herein shown and described only two forms of railway signaling apparatus embodying my invention, it is understood that various changes and modifications may be made therein within the scope of the appended claims without departing from the spirit and scope of my invention.

Having thus described my invention, what I claim is:

1. In combination, a section of railway track through which are operated locomotives equipped with cab signal apparatus responsive to flow of alternating current in excess of a predetermined value in the track rails in advance of the locomotive and effective to provide a proceed indi-

cation only when said alternating current is coded, and means for alternately supplying to the section rails at the exit end of the section impulses of alternating current energy of a voltage high enough to cause energy in excess of said predetermined value to be present in the section rails throughout the section and of alternating current energy of a voltage effective to cause energy in excess of said predetermined value to be present only in the portion of the section rails within a predetermined distance of the exit end of the section.

2. In combination, a section of railway track through which are operated locomotives equipped with cab signal apparatus responsive to flow of alternating current in excess of a predetermined value in the track rails in advance of the locomotive and effective to provide a proceed indication only when said alternating current is coded, a first source of alternating current of a voltage high enough to cause energy in excess of said predetermined value to be present in the section rails throughout the section, a second source of alternating current of a voltage effective to cause energy in excess of said predetermined value to be present only in the portion of the section rails within a predetermined distance from the exit end of the section, and means for alternately supplying to the track rails at the exit end of the section impulses of energy from said first and said second sources.

3. In combination, a section of railway track through which are operated locomotives equipped with cab signal apparatus responsive to flow of alternating current in excess of a predetermined value in the track rails in advance of the locomotive and effective to provide a proceed indication only when said alternating current is coded, a first source of alternating current of a voltage high enough to cause energy in excess of said predetermined value to be present in the section rails throughout the section, a second source of alternating current of a voltage effective to cause energy in excess of said predetermined value to be present only in the portion of the section rails within a predetermined distance from the exit end of the section, means for supplying from said first source to the section rails at the exit end of the section impulses of energy which are separated by "off" periods during which the supply of energy from said first source is interrupted, and means for supplying energy from said second source to the section rails at the exit end of the section during the "off" periods in the supply of energy from said first source.

4. In combination, a section of railway track through which are operated locomotives equipped with cab signal apparatus responsive to flow of alternating current in excess of a predetermined value in the track rails in advance of the locomotive and effective to provide a proceed indication only when said alternating current is coded, a first source of alternating current of a voltage high enough to cause energy in excess of said predetermined value to be present in the section rails throughout the section, a second source of alternating current of a voltage effective to cause energy in excess of said predetermined value to be present only in the portion of the section rails within a predetermined distance from the exit end of the section, means for supplying from said second source to the section rails at the exit end of the section impulses of energy which are separated by "off" periods during which the supply of energy from said source is interrupted,

and means responsive to the supply of energy from said second source of energy to the section rails for supplying energy from said first source to the section rails at the exit end of the section during the "off" periods in the supply of energy from said second source to the section rails.

5. In combination, a section of railway track through which are operated locomotives equipped with cab signal apparatus responsive to flow of alternating current in excess of a predetermined value in the track rails in advance of the locomotive and effective to provide a proceed indication only when said alternating current is coded, a first source of alternating current of a voltage high enough to cause energy in excess of said predetermined value to be present in the section rails throughout the section, a second source of alternating current of a voltage effective to cause energy in excess of said predetermined value to be present only in the portion of the section rails within a predetermined distance from the exit end of the section, and a coding device having a contact continuously moved between a first and a second position, a contact of said coding device being effective when in its first position to establish a circuit for supplying energy from said first source to the section rails at the exit end of the section, a contact of said coding device being effective when in its second position to establish a circuit for supplying energy from said second source to the section rails at the exit end of the section.

6. In combination, a section of railway track through which are operated locomotives equipped with cab signal apparatus responsive to flow of alternating current in excess of a predetermined value in the track rails in advance of the locomotive and effective to provide a proceed indication only when said alternating current is coded, a first source of alternating current of a voltage high enough to cause energy in excess of said predetermined value to be present in the section rails throughout the section, a second source of alternating current of a voltage effective to cause energy in excess of said predetermined value to be present only in the portion of the section rails within a predetermined distance from the exit end of the section, a coding device having a contact continuously moved between a first and a second position, a contact of said coding device being effective when in its first position to establish a circuit for supplying energy from said first source to the section rails at the exit end of the section, a contact of said coding device being effective when in its second position to establish a circuit for supplying energy from said second source to the section rails at the exit end of the section, and means responsive to the supply of energy from said second source to the section rails and controlling the supply of energy from said first source to the section rails.

7. In combination, a section of railway track through which are operated locomotives equipped with cab signal apparatus responsive to flow of alternating current in excess of a predetermined value in the track rails in advance of the locomotive and effective to provide a proceed indication only when said alternating current is coded, a first source of alternating current of a voltage high enough to cause energy in excess of said predetermined value to be present in the section rails throughout the section, a second source of alternating current of a voltage effective to cause energy in excess of said predetermined value to be present only in the portion of the section rails within a predetermined distance from the exit end of the section.

end of the section, and a coding device having contacts continuously moved between a first and a second position, a contact of said coding device being effective when in its second position to establish a circuit for supplying energy from said second source to the section rails at the exit end of the section in series with the winding of an auxiliary relay, a contact of said coding device being effective when in its first position to establish a circuit including a front contact of said auxiliary relay for supplying energy from said first source to the section rails at the exit end of the section.

8. In combination, a stretch of railway track through which are operated locomotives equipped with cab signal apparatus responsive to flow of alternating current in excess of a predetermined value in the track rails in advance of the locomotive and effective to provide a proceed indication only when said alternating current is coded, the rails of said track stretch being divided by insulated joints into a plurality of track sections including a forward and a rearward section, a first source of alternating current of a voltage high enough to cause energy in excess of said predetermined value to be present throughout the rails of a track section, a second source of alternating current of a voltage effective to cause energy in excess of said predetermined value to be present only in the portion of the rails of a section within a predetermined distance from the exit end of the section, means effective when said forward section is vacant for supplying to the rails of said rearward section at the exit end of said section energy from said first source coded at a first rate, and means effective when said forward section is occupied to supply to the rails of said rearward section at the exit end of said section energy from said first source coded at a second rate and to also supply to the section rails energy from said second source in the periods between the impulses of coded energy supplied from said first source.

9. In combination, a stretch of railway track through which are operated locomotives equipped with cab signal apparatus responsive to flow of alternating current in excess of a predetermined value in the track rails in advance of the locomotive and effective to provide a proceed indication only when said alternating current is coded, the rails of said track stretch being divided by insulated joints into a plurality of track sections including a forward and a rearward section, a first source of alternating current of a voltage high enough to cause energy in excess of said predetermined value to be present throughout

the rails of a track section, a second source of alternating current of a voltage effective to cause energy in excess of said predetermined value to be present only in the portion of the rails of a section within a predetermined distance from the exit end of the section, means effective when said forward section is vacant for supplying to the rails of said rearward section at the exit end of said section energy from said first source coded at a first rate, and means effective when said forward section is occupied to supply to the rails of said rearward section at the exit end of the section over a circuit including the front contact of an auxiliary relay energy from said first source coded at a second rate and to also supply to the rails of said rearward section over a circuit including the winding of said auxiliary relay in series therewith energy from said second source in the periods between the impulses of coded energy supplied from said first source.

10. In combination, a stretch of railway track through which are operated locomotives equipped with cab signal apparatus responsive to flow of alternating current in excess of a predetermined value in the track rails in advance of the locomotive and effective to provide a proceed indication only when said alternating current is coded, the rails of said track stretch being divided by insulated joints into a plurality of track sections including a forward and a rearward section, a first source of alternating current of a voltage high enough to cause energy in excess of said predetermined value to be present throughout the rails of a track section, a second source of alternating current of a voltage effective to cause energy in excess of said predetermined value to be present only in the portion of the rails of a section within a predetermined distance from the exit end of the section, means effective when said forward section is occupied to supply to the rails of said rearward section at the exit end of the section over a circuit including the front contact of an auxiliary relay energy from said first source coded at a second rate and to also supply to the rails of said rearward section over a circuit including the winding of said auxiliary relay in series therewith energy from said second source in the periods between the impulses of coded energy supplied from said first source, and means effective when said forward section is vacant to supply to the rails of said rearward section at the exit end of the section over a circuit independent of said auxiliary relay energy from said first source coded at a first rate.

HOWARD A. THOMPSON.
